UNITED STATES PATENT OFFICE.

JACOB CLOOS, OF MILWAUKEE, WISCONSIN, ASSIGNOR TO THE CLOOS ELECTRICAL ENGINEERING COMPANY, OF SAME PLACE.

SWITCHING APPARATUS.

SPECIFICATION forming part of Letters Patent No. 623,118, dated April 11, 1899.

Application filed February 7, 1898. Serial No. 669,294. (No model.)

To all whom it may concern:

Be it known that I, JACOB CLOOS, a citizen of the United States, residing at Milwaukee, in the county of Milwaukee and State of Wisconsin, have invented a certain new and useful Improvement in Switching Apparatus, (Case No. 2,) of which the following is a full, clear, concise, and exact description.

My invention relates to switching apparatus for controlling the distribution of electricity, and more particularly currents of high potential, and has for its object, first, the provision of an improved form of switching apparatus wherein the switch parts are thoroughly protected and made weather-proof; second, the construction of a switch whereby the circuit changes are effected in a predetermined order in a manner to avoid certain objections heretofore present in switching mechanism; third, the provision of a switch wherein plugs form circuit-changing parts which are simultaneously operated by lever mechanism, and, fourth, the simplification and improvement of the stationary portions of the switching mechanism.

My invention consists in apparatus designed to accomplish the above objects, and, generally speaking, in its preferred form may be described as consisting of an oscillating actuating-lever with plug suspended thereon and a base-plate supporting at its upper and lower portions thimbles which are adapted to be engaged by the plugs or which in part are disengaged from the plugs in effecting the required circuit changes. This mechanism is preferably disposed in a weather-proof box, in which oil is provided to immerse the switch parts, the oscillating lever being preferably connected with a reciprocating rod extending through a stuffing-box to the exterior, the exterior portion of the reciprocating rod being provided with a handle for operating the switching apparatus.

I will explain my invention more particularly by reference to the accompanying drawings, which illustrate the preferred embodiment thereof.

In the drawings, Figure 1 is a plan view of the switching apparatus in place within a junction-box, a circuit to which this apparatus is suited being indicated by dotted lines.

Fig. 2 is a sectional elevation on line 2 2 of Fig. 1. Fig. 3 is a perspective view of a pair of thimbles entering into the construction of the switching apparatus. Fig. 4 is a diagrammatic view showing the circuit-changing portions of the apparatus as associated with a working circuit.

Like letters indicate like parts throughout the different views.

I will first describe the mechanical construction of my improved switching apparatus and will then state in what manner it is employed. The supports for the thimbles q q' q^2 q^3 and the thimbles r r' r^2 r^3 consist, preferably, of the insulating-base s , anchored to the box, the upper portion of which base forms the support for the thimbles q q' q^2 q^3 , while the lower portion thereof forms a support for the thimbles r r' r^2 r^3 . By providing the supports for the thimbles in a single piece the alinement of opposed thimbles is absolutely fixed, so that the plugs are accurately guided into engagement with alined thimbles. The upper thimbles are provided with suitable stems adapted for connection with the circuit conductors. The thimbles r and r' are electrically connected. The thimbles r^2 and r^3 are connected, respectively, with thimbles q q' . The plugs t t' t^2 t^3 are pivotally mounted upon the ends of a centrally-pivoted oscillating lever u , the plugs being insulated from said lever. Slots are provided in the lever to permit the pivot-pins uniting the plugs therewith to move longitudinally with relation to the lever u as the lever is oscillated. A central extension of the lever u is connected with the reciprocating rod v , extending through a stuffing-box v' in a wall of the junction-box w .

A packing w' is preferably interposed between the cover w^2 and the top of the junction-box. The plugs are preferably provided with longitudinal slits, as illustrated, to permit the same to have a spring-like engagement with the thimbles. Oil, preferably kerosene, is provided within the junction-box, in which the switch parts are immersed, as shown in Fig. 2.

The system of distribution to which the switch shown is especially adapted is illustrated in Fig. 4.

The feeders extending from the generator are connected with the contact portions or thimbles $q' q^2$ and $r^2 r^3$. The loop-circuit y has its terminals connected with the thimbles 5 or contact portions $q' q^3$. The thimbles and plugs are preferably so relatively disposed that the plugs upon either end of the oscillating lever u will connect the alined thimbles associated therewith before the plugs 10 upon the other end of the switch-lever are moved sufficiently to disconnect the thimbles in engagement therewith.

By mounting the circuit switch-plugs upon a switch-lever the changes in the circuit conditions are effected in a uniform and predetermined manner. Other flexible connection with the switch-lever than a pivotal connection may be employed.

It is obvious that departures may be made 20 from the preferred embodiment of the invention herein shown and particularly described, and I do not therefore desire to be limited to the precise construction shown; but,

Having thus described my invention, what 25 I claim as new, and desire to secure by Letters Patent, is—

1. In a switch, the combination with a pivotally-mounted switch-lever, of plugs $t' t'$ flexibly connected with said lever upon one side 30 of the pivot, plugs $t^2 t^3$ flexibly connected with said lever upon the other side of its pivot, contact-thimbles $q' q^2$, $r^2 r^3$ normally connected with the feeders, electrically-connected thimbles $r r'$ alined respectively with thimbles $q' q^2$, and thimbles $q' q^3$ forming terminals of a loop or distribution-circuit alined respectively with thimbles $r^2 r^3$, the plugs upon the switch-lever being adapted to connect alined thimbles, substantially as described.

40 2. In a switch, the combination with a piv-

otally-mounted switch-lever, of plugs $t' t'$ flexibly connected with said lever upon one side of the pivot, plugs $t^2 t^3$ flexibly connected with said lever upon the other side of its pivot, contact-thimbles $q' q^2$, $r^2 r^3$ normally connected with the feeders, electrically-connected thimbles $r r'$ alined respectively with thimbles $q' q^2$, and thimbles $q' q^3$ forming terminals of a loop or distribution-circuit alined respectively with thimbles $r^2 r^3$, the plugs upon the switch-lever being adapted to connect alined thimbles, the plugs and thimbles being so relatively disposed that the plugs upon either side of the pivot of the lever connect the thimbles associated therewith, before the 55 plugs upon the other side of the switch-lever break connection between the thimbles associated therewith, substantially as described.

3. The combination with a pivotally-mounted switch-lever, of plugs $t' t'$ flexibly connected with said lever upon one side of the pivot, plugs $t^2 t^3$ flexibly connected with said lever upon the other side of its pivot, contact-thimbles $q' q^2$, $r^2 r^3$ normally connected with the feeders, electrically-connected thimbles $r r'$ 65 alined respectively with thimbles $q' q^2$, thimbles $q' q^3$ forming terminals of a loop or distribution-circuit alined respectively with thimbles $r^2 r^3$, the plugs upon the switch-lever being adapted to connect alined thimbles, 70 a box for the above-described switching mechanism, and oil within the box in which the mechanism in part is disposed, substantially as described.

In witness whereof I hereunto subscribe my 75 name this 31st day of January, A. D. 1898.

JACOB CLOOS.
